(57) **CLAIM**

The ornamental design for a garlic peeler, as shown and described.

DESCRIPTION

FIG. 1 is a top, front, right side perspective view of a garlic peeler;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The long-dash short-dash boundary lines represent boundaries of the claimed design and form no part thereof. All other broken lines illustrate portions of the garlic peeler that form no part of the claimed design
